United States Patent Office

Des. 229,897

Patented Jan. 15, 1974

229,897

POUR-IN TYPE BEVERAGE MAKER

John C. Martin, Springfield, Ill., assignor to Bunn-O-Matic Corporation, Springfield, Ill.

Filed May 8, 1972, Ser. No. 251,587

Term of patent 14 years

Int. Cl. D7—02

U.S. Cl. D7—85

FIG. 1 is a perspective view looking from the top, front and left sides of a pour-in type beverage maker embodying my design.

FIG. 2 is a perspective view thereof looking from the top, rear and right sides.

I claim:

The ornamental design for a pour-in type beverage maker, substantially as shown and described.
